UNITED STATES PATENT OFFICE

126,370

DESIGN FOR A PLATE OR SIMILAR ARTICLE

Willis O. Prouty, Hermosa Beach, Calif.

Application September 25, 1939, Serial No. 87,370

Term of patent 14 years

To all whom it may concern:

Be it known that I, Willis O. Prouty, a citizen of the United States and a resident of Hermosa Beach, in the county of Los Angeles and State of California, have invented a new, original, and ornamental Design for a Plate or Similar Article, of which the following is a specification, reference being had to the accompanying drawing, forming part thereof, in which:

article, showing my design, the ornamentation shown between the two broken lines being continued throughout the border of the plate; and

I claim:

The ornamental design for a plate or similar article, substantially as shown and described.

WILLIS O. PROUTY.
